Inventor
W. R. Cornelius,

By *Geo. P. Kimmel*
Attorney

UNITED STATES PATENT OFFICE.

WILLIAM R. CORNELIUS, OF NASHVILLE, TENNESSEE.

REVERSIBLE CUFF.

Application filed October 24, 1923. Serial No. 670,561.

To all whom it may concern:

Be it known that I, WILLIAM R. CORNELIUS, a citizen of the United States, residing at Nashville, in the county of Davidson and 5 State of Tennessee, have invented certain new and useful Improvements in Reversible Cuffs, of which the following is a specification.

This invention relates to soft cuffs, particularly to what is known as the soft cuff of the French type, and has for its object to provide, in a manner as hereinafter set forth, a cuff of such class, with means for holding the edge formed by the bend when 10 the cuff is folded normally or reversed aloof from the wrist, as well as for absorbing the oil from the skin when the cuff is worn, whether in normal or reverse position, whereby wear on said edge is reduced to a minimum, the soiling of such edge is materially 15 delayed and the life of the cuff prolonged.

The most vulnerable part of a shirt of that type provided with a soft cuff is the edge formed at the bend of the cuff, and the chief 20 cause for the fraying of such edge is the absorption of waste matter from the pores of the skin, such matter is a liquid acid of an oily nature, which impregnating the threads of the fabric at such edge creates the deterioration or rotting, whereby the life 25 thereof is materially decreased, and further destructive agents of the threads at such edge are ironing and friction. To overcome such deteriorating action on the edge of the 30 cuff is the primary object of this invention and to attain such object the invention resides in setting up a foldable soft cuff, in a manner as hereinafter set forth, whereby it does not necessitate the folding of the cuff 35 when ironing and whereby the points of contact of the cuff with the skin which absorb the waste matter are positioned inwardly with respect to the edge of the bend so that 40 absorption will take place at a point removed from such edge thereby increasing the life 45 of the latter, and furthermore when the cuff is ironed in a flat position the ironing element does not come in contact with bent, twisted threads as would be the case if the 50 cuff is folded, but on straight or flat threads.

A further object of the invention is to provide, in a manner as hereinafter set forth, a

soft cuff body having means to prevent a sharp crease when the cuff is folded and furthermore whereby said means will enable 55 the cuff body to be folded at the point of least resistance, and furthermore whereby when the cuff is folded the folds will be uniform whether the cuff body is folded to normal or from normal position, that is to say, 60 from normal to reverse position.

Further objects of the invention are to provide, in a manner as hereinafter set forth, a cuff of the soft type, with an interlining formed with a pair of spaced offset portions 65 arranged in proximity to the longitudinal center thereof to constitute means to provide for a warning if imprints shown in the outer cuff covering to remove the heated ironing element off of threads which have absorbed 70 the oil from the skin; act as added thicknesses to the inter-lining to keep the ironing element off the threads that are in the actual line of the fold; to create a trough so a sharp edge crease will not be made and a reverse 75 fold not show puckering and wrinkling; to hold the cuff slightly aloof from the wrist; to absorb perspiration and to maintain the edge formed by the bend of the fold clear 80 of the wrist.

Further objects of the invention are to provide a reversible soft cuff, which is comparatively simple in its construction and arrangement, strong, durable, having a smooth appearance when folded normally or reversed, 85 set up with respect to the shirt sleeve to enable the cuff body to be ironed flat, and inexpensive to manufacture.

With the foregoing and other objects in view, the invention consists of the novel construction, combination and arrangement of parts as hereinafter more specifically described and illustrated in the accompanying drawings, wherein is shown an embodiment 90 of the invention, but it is to be understood that changes, variations and modifications can be resorted to which come within the scope of the claims hereunto appended.

In the drawings wherein like reference characters denote corresponding parts 100 throughout the several views:

Figure 1 is an elevation of a cuff in accordance with this invention, extended and broken away, to illustrate the inter-lining.

Figure 2 is a perspective view of the inter-lining showing a part of each of the offset portions disconnected and raised.

Figure 3 is an enlarged fragmentary view in section of the cuff when folded in normal position.

Figure 4 is a similar view of the cuff folded in reverse position.

Figure 5 is an edge view of the form of inter-lining shown in Figure 2.

Figure 6 is a view similar to Figure 5 of a modified form of interlining.

Referring to the drawings in detail, 1 denotes a shirt sleeve and 2 generally a reversible soft cuff set up in accordance with this invention, and which is formed from a rectangular body portion having its inner longitudinal edge for a portion of its length secured to the outer terminus of the sleeve 1, by a row of stitching 3. The body portion of the cuff is so set up with respect to the sleeve 1, whereby the end terminal portions 4, of the inner edge of the cuff body will project slightly from the sleeve 1. By connecting the cuff body to the sleeve in a manner as stated, the cuff body can be extended and ironed flat, or can be extended to lay in a flat position, as shown in Figure 1, so that the cuff body can be ironed flat throughout providing for the smooth ironing of said body.

The cuff body is formed from an outer section 6, and a rear section 7, of any suitable fabric, and each of said sections is rectangular in contour, of the desired width and of the same size. The marginal portions of each of the sections are inturned against the inner face of the sections, which is the ordinary manner of setting up the sections of a cuff body. The sections 6 and 7 are not only secured together by the row of stitching 3, but also by a row of stitching 8, which extends transversely and longitudinally of said sections and which is arranged in proximity to the end edges as well as to the outer longitudinal edge of the sections. The sleeve 1 extends between the sections 6 and 7 and as before stated is secured therewith by the row of stitching 3. The row of stitching 3 extends in close proximity to the end edges of the sections 6, 7, and projects outwardly with respect to the transversely extending portions of the row of stitching 8. The stitching 3, as well as stitching 8, secured the inturned marginal portions of the sections together as well as securing said sections together.

Positioned between the sections 6 and 7, is an interlining 9, which is of the same contour as the shape of the sections 6 and 7 and is fixedly secured in position by the rows of stitching 3 and 8. When the interlining 9 is arranged between the sections, it is extended between the inturned marginal portions of one of said sections 6 or 7. The

material from which the inter-lining 9 is set up is unusually light and is known as "44-40" and of a weight of five yards to the pound and which provides an unusually light material.

Prior to the positioning of the inter-lining 9 between the sections 6 and 7, the said inter-lining is formed with a pair of spaced lengthwise extending offset portions or ribs and with reference to Figures 1, 2, 3, 4 and 5, said offset portions are indicated at 10 and 11, and with reference to Figure 6, said offset portions are indicated at 12, 13.

With reference to Figures 1 to 5, the offset portion or rib 10 is of greater width than the offset portion or rib 11, and the said offset portions 10 and 11 are of the same length as the length of the body of the inter-lining and are arranged in proximity to the longitudinal center of the inter-lining, but spaced therefrom, and said longitudinal center of the inter-lining will be positioned at the edge formed by the bend when the cuff body is folded either to normal or from normal to reverse position.

The offset portions or ribs 10 and 11 are substantially similar to a tuck, and the offset portion 10 is formed by providing a part of the inter-lining with a pair of folds 14, 15, and with the fold 14 extending towards one longitudinal edge, and the fold 15 toward the other longitudinal edge of the inter-lining. The fold 14 is positioned against one face of the body portion, and the fold 15 is arranged against the fold 14. The fold 15 is of materially greater width than the fold 14 and projects from the fold 14, as at 17. The folds 14 and 15 are secured together by a row of stitching 18, and the folds 14 and 15 are connected together and also secured to the body portion of the inter-lining by a row of stitching 19.

The offset portion or rib 11 is set up by providing a part of the inter-lining with a pair of folds 20, 21, and with the latter positioned against the face 22 of the body portion of the inter-lining. The fold 20 forms a continuation of the extension 17 and is secured to the fold 21 by a row of stitching 23. The folds 20 and 21 are secured together and also secured to the body portion of the inter-lining by a row of stitching 24.

The bend between the body portion of the inter-lining and fold 14 is indicated at 25, the bend between the folds 14 and 15 is indicated at 26. The bend between the body portion and fold 21 is indicated at 27, and the bend between the folds 20 and 21 is indicated at 28. The row of stitching 19 is arranged to one side of the bend 26 and the row of stitching 18 is arranged to one side of the bend 25, and said row of stitching 18 does not engage with the body portion of the inter-lining. The row of stitching 24 is arranged to one side of the bend 28 and 130

engages with the body portion of the inter-lining. The row of stitching 23 is to one side of the bend 27 and does not engage with the body portion of the inter-lining.

5 The extension 17 projects from under the bend 25 and up and over the bend 27, whereby said extension is disposed at a slight inclination and provides what may be termed a trough 29 in front of the bend 25, and a trough 30 in front of the bend 27.

10 The offset portion or rib 10 is of greater width than the offset portion or rib 11 and the said offset portions or ribs are arranged on opposite faces of the body portion of the 15 inter-lining.

In the form shown in Figure 6, the offset portions or ribs 12 and 13 are arranged on the same side of the body portion of the inter-lining 31. The offset portions or ribs 20 12 and 13 are connected together by what may be termed an extension 32 of the outer fold which constitutes a part of the offset portion or rib 12. The offset portion or rib 12, as well as offset portion or rib 13, is 25 set up of two folds and with the folds connected together and also with the folds connected together and to the body portion of the inter-lining. The offset portion or rib 12 is spaced from the offset portion or rib 30 13 and arranged between said offset portions is what may be termed a trough 33.

The advantage of setting up one narrow and one wide offset portion or rib, is, if the 35 folds are of the same width they overlap or rather lie on top of one another in such manner that the edges would be one on top of the other. The iron when it strikes the edges would cause imprints, but with the wide and narrow offsets or ribs, the narrow rib will 40 bed in the wide rib and the iron will strike on one increased thickness at a time and will not make an imprint. In wearing the cuff, the wide rib will bend over the narrow rib and not make an imprint in the outer cuff 45 covering.

The space or trough between the ribs allows the threads of the outer shirt covering of the cuff to be always free, and in washing, the liquid used to cleanse will dissolve the 50 dirt in these threads most freely and the solution of soap, water, and dirt will be easily rinsed, without hard scrubbing of the most vulnerable part of the cuff and if starch is used the threads of this weak point 55 of the cuff will not be cemented together, being separated from the inter-lining by the thickness of the cushion bevel.

The object in establishing this underlying space or trough is to prevent a sharp edge 60 crease in the inter-lining or in the outer shirt cuff covering when ironed or when folded. If the cuff is ironed flat the threads at the point above the space created sink into this space and if the wearer wants to fold the 65 cuff it will fold at the point of least resist-

ance. If the cuff is folded by the person who is ironing or by the operator of the machine known as the "cuffer" in the laundry, the psychological tendency will be to match the four corners of the rectangular shaped cuff 70 and this will be the cause of bringing the fold line in the proper place or about in the center of the cuff. The ironing element will ride on or rest upon the cushions if the cuff is folded to be ironed and a sharp crease is 75 not possible to make, thereby prolonging the life of the threads at this point by never breaking them by ironing. As no interior angle is formed in original ironing of or folding of the cuff the reversing of the cuff 80 will disclose no evidence of having been creased and as no interior angle was made, but a concave effected by original folding, the reversed flap which has been turned under the flap that is attached to the sleeve 85 will stay in its place as there will not be the usual broken interior angle or irregular crease line that occurs in the present folded soft cuff, because when a reflex angle is made by folding cloth, an interior angle is made 90 to correspond and as this can not be done without wrinkling the material that lies along the crease line by the crease line made when the cuff is damp or dry, the only way to overcome this objection is to prevent interior and reflex angles and resort to concave and convex curves, and this has been done by the formation of a trough referred to above by the employment of the offset portions or ribs or what may be termed 95 cushions.

These cushions will act as bands to hold the cuff edge aloof from the wrist and will absorb the oil from the skin as the band that is worn on the forehead of the tennis player. 100 This not only delays soiling the cuff edge but minimizes the absorption of deleterious matter and prolongs the life of the cuff, and such absorption is variable at each wearing.

Although the preferred embodiment of a 105 soft cuff, in accordance with this invention is as illustrated and described, yet it is to be understood that changes in the details of construction can be had which will fall within in the light of the invention as claimed.

110 What I claim is:—

1. A soft cuff comprising a foldable, flexible body portion formed of a pair of complementary sections having arranged therebetween and secured therewith an inter-lining, said inter-lining having two spaced pairs of lengthwise extending folds providing a pair of offset portions arranged on opposite sides and spaced from the bend formed in the cuff body when the latter 115 is folded.

2. A soft cuff comprising a foldable, flexible body portion formed of a pair of complementary sections having arranged therebetween and secured therewith an inter- 120 125 130

lining, said inter-lining having two spaced pairs of lengthwise extending folds providing a pair of offset portions arranged on opposite sides and spaced from the bend formed in the cuff body when the latter is folded, one of said offset portions being of greater width than the other.

3. A soft cuff comprising a foldable, flexible body portion formed of a pair of complementary sections having arranged therebetween and secured therewith an inter-lining, said inter-lining having two spaced pairs of lengthwise extending folds providing a pair of offset portions arranged on opposite sides and spaced from the bend formed in the cuff body when the latter is folded, means for securing the folds of each pair together, and means for securing the folds of each pair together and to the body 20 of the inter-lining.

4. A soft cuff comprising a foldable, flexible body portion formed of a pair of complementary sections having arranged therebetween and secured therewith an inter-lining, said inter-lining having two spaced pairs of lengthwise extending folds providing a pair of offset portions arranged on opposite sides and spaced from the bend formed in the cuff body when the latter is folded, one of said offset portions arranged upon one face of the inter-lining and the other of said offset portions arranged upon the other face of the inter-lining.

5. A soft cuff comprising a foldable, flexible body portion formed of a pair of complementary sections having arranged therebetween and secured therewith an inter-lining, said inter-lining having two spaced pairs of lengthwise extending folds providing a pair of offset portions arranged on opposite sides and spaced from the bend formed in the cuff body when the latter is folded, one of said offset portions arranged

upon one face of the inter-lining and the other of said offset portions arranged upon the other face of the inter-lining, and one of said offset portions being of greater width than the other offset portion.

6. A soft cuff comprising a foldable, flexible body portion formed of a pair of complementary sections having arranged therebetween and secured therewith an inter-lining, said inter-lining having two spaced pairs of lengthwise extending folds providing a pair of offset portions arranged on opposite sides and spaced from the bend formed in the cuff body when the latter is folded, one of said offset portions arranged upon one face of the inter-lining and the other of said offset portions arranged upon the other face of the inter-lining, and one of said offset portions being of greater width than the other offset portion, a row of stitching 55 for securing each pair of folds together in proximity to a bend between the body of the inter-lining and a fold of the pair, and a row of stitching for securing the folds of a pair together in proximity to the bend therebetween and further for securing said folds to the body of the inter-lining.

7. A soft cuff comprising a foldable, flexible body portion formed of a pair of complementary sections having arranged therebetween and secured therewith an inter-lining folded to provide a pair of fixed offset portions spaced from each other and arranged on opposite sides of the bend formed by said body portion when the latter is folded, said offset portions in connection with the body of the inter-lining constituting a trough forming means medially of the inter-lining.

In testimony whereof, I affix my signature hereto.

WILLIAM R. CORNELIUS.
